UNITED STATES PATENT OFFICE.

DAVID BOURLAND, OF MADISONVILLE, KENTUCKY.

IMPROVEMENT IN CANDLESTICKS.

Specification forming part of Letters Patent No. 148,106, dated March 3, 1874; application filed January 31, 1874.

To all whom it may concern:

Be it known that I, DAVID BOURLAND, of Madisonville, in the county of Hopkins and State of Kentucky, have invented a new and useful Improvement in Candlesticks, of which the following is a specification:

Figure 1 is a detail vertical section of my improved candlestick, and Fig. 2 is a top view of the same.

Similar letters of reference indicate corresponding parts.

My invention has for its object to furnish an improved candlestick, which shall be so constructed as to hold the candle securely until it is entirely consumed, and which entirely prevents the difficulty arising from the lower end of the candle sticking fast in the socket of the candlestick, so that it cannot be raised by the pusher.

The invention consists in the combination of the pivoted clamps and their spring or springs with the pedestal or post of the candlestick, closed at the upper end, as hereinafter fully described.

A represents the base or saucer of the candlestick, which is made in the ordinary form or manner, and has a pedestal or post, B, attached to its center, in the ordinary way. The upper end of the post B is closed, and to it are pivoted two semi-tubular clamps or levers, C, the upper ends of which project beyond the top of the pedestal B, and which may have semicircular flanges or shelves, c', formed upon their inner or concave sides, just above the

top of the post or pedestal B, for the lower end of the candle to rest upon. The lower ends of the semi-tubular clamps C extend nearly to the base or bottom A of the candlestick. D are springs attached to the upper part of the post B, and pressing the lower ends of the clamps C outward, so as to clamp the candle between the upper ends and hold it securely. The springs D may be made in one piece, and in V shape, and may be passed through and secured in a hole in the upper end of post B. If desired, one of the clamps C may be stationary, and the other pivoted and provided with a spring; but I prefer the construction first described, as holding the candle more erect.

In using the candlestick, the upper ends of the clamps C are forced apart, for inserting and removing the candle, by pressing the lower ends of said clamps inward with the thumb and finger.

Having thus described my invention, I claim as new and desire to secure by Letters Patent—

In combination with the base A and pedestal B, the semi-cylindrical pivoted clamps C C', provided with internal supports or ledges C' C', and with an interposed spring or springs, D, the various parts being constructed and relatively combined as set forth and shown.

DAVID BOURLAND.
